UNITED STATES PATENT OFFICE.

JAMES J. STEVER, OF OWOSSO, MICHIGAN.

CAR-AXLE BOX.

SPECIFICATION forming part of Letters Patent No. 375,217, dated December 20, 1887.

Application filed February 12, 1887. Serial No. 227,392. (No model.)

To all whom it may concern:

Be it known that I, JAMES J. STEVER, a citizen of the United States, residing at Owosso, in the county of Shiawassee and State of Michigan, have invented certain new and useful Improvements in Car-Oilers, of which the following is a specification.

Heretofore in the oil-boxes of railway car axles it has been customary to pack within the box a quantity of saturated waste, the said waste being so arranged around the bearing of the axle that loss of oil or lubricating material was unavoidable, inasmuch as there is nothing to prevent the oil from running out at the rear side of the journal-box. As the result of this, the oil spreads out and flows along the axle until it comes to the wheels, at which point it commences to drip, entailing an enormous loss of valuable oil.

Another drawback to the ordinary means of oiling the bearings of car-axles is that the jar of the cars causes the waste and oil in the journal-box to drop down and away from the axle, and as soon as it settles and falls away from the bearing the axle will become dry and heated, and the friction generating will set the waste and oil on fire. This has often occurred and is the immediate cause of great loss in railway property.

To obviate these drawbacks and to provide a simple, effective, and automatic oiler for the bearings of railway-car axles are the objects of my invention.

Referring to the accompanying drawings, which form a part of this specification, Figure 1 is a plan view of my invention. Fig. 2 is a longitudinal section of a journal-box with my invention applied. Fig. 3 is an end elevation without the journal-box, the journal being in section.

A is an axle having a bearing-surface formed on its journal B, and C is the journal-box, in which the oil is held.

D is a frame provided with lugs E, which form bearings for a pin or pivot or hinge, F. Arms or levers G are journaled to this pivot, and these arms or levers constitute a frame having a pin, H, connecting their upper extremities, said pin H forming the axle or shaft of a rotatable wheel, J, having centrally-located incisions K upon its periphery, thus forming a roller with a centrally corrugated

or fluted area with a plain area on both sides, whereby the oil is conveyed to the journal, and at the same time the journal is protected against any detriment by the corrugations, and the corrugations are protected against any detriment by the journal. A spring, L, is provided, which is attached to the frame at M, and extends around the hinge F, and bears under the cross-piece N of the frame G, and serves to support said frame at an angle, as shown in Fig. 3, and by this means keeps the wheels J against the bearing B of the axle. As the axle rotates it will bear upon the peripheries of the wheel J, which movement will cause them to rotate also, and as the oil is located in the bottom of the oil-box the wheels J as they rotate will carry the said oil to the bearing-surface of the axle by means of the indented portions K. By this means the bearing-surfaces are kept constantly oiled, and the springs, keeping the rotating wheels against the axle, will lubricate the bearings as long as there is oil in the box. I also provide a stop or collar, S, having shoulders at both ends, which slide on uprights T, said collar being also provided with a supporting-spring, U, for the purpose of keeping it constantly against the bearing of the axle, and thus preventing any oil from passing in that direction and toward the wheel. It will thus be seen that any oil that has passed as far back as the collar S will be turned back into the journal-box again, and thus all waste from this source is prevented.

I am aware that it has been proposed to cushion beneath a journal rotatable rollers provided with corrugations, and the same being fluted throughout their length for conveying the lubricant to the journal; but this is not the equivalent of my invention, nor do I wish to claim the same. In my invention the corrugations only extend a portion of the way across the periphery of the roller, thereby leaving a plain surface on each side, which portion bears against the journal and prevents the cushion-springs from subjecting the journal to pressure against the sharp edges of the corrugations.

Therefore, what I claim as new, and wish to secure by Letters Patent, is--

1. The combination of the base-frame D, having paired lugs E E, E E, pins F, sup-

ported in the lugs, inwardly-extending frames having arms G G, G G, and cross-bars N N, rollers J J, journaled in the ends of the arms, and the springs L L, secured to the base-frame and bearing on the cross-bar, substantially as described.

2. The combination of the base-frame D, uprights T T, collar S, sliding on the uprights,

and a spring, V, secured to the base-frame and supporting the collar, substantially as described.

JAMES J. STEVER.
